RAIL PULLER

Raymond Lynn Shambaugh, West Lafayette, Ind.

Application March 13, 1941, Serial No. 383,118

16 Claims. (Cl. 254—104)

This invention relates to a device for lifting rails, particularly for lifting rails such as street car rails which are embedded in a pavement.

The rails of street car tracks are usually embedded in the pavement of a street, with the upper surface of the rails level with the upper surface of the street. The rails are spiked down on ties which lie below the surface of the pavement and often below the pavement itself. When the street car service is abandoned, it is desirable to remove the rails. This is partly because the rails have considerable salvage value, and partly because in re-paving the street it is desirable to have the rails removed. The ties, however, have little or no salvage value and their presence beneath the pavement offers very little disadvantage. In this situation, it is desirable in removing the rails to do so without disturbing the ties, and without disturbing any more of the original pavement than is necessary.

It is the object of my invention to provide a device which will remove the rails from a pavement in which they are embedded, without disturbing the ties, and with a minimum disturbance of the pavement; and which will do this inexpensively. In addition, it is my object to provide a device which will remove rails quickly, not only to reduce expense, but so that the street may be taken out of service for a minimum amount of time.

In accomplishing these purposes, I provide a rail-lifting device which comprises a pair of runners adapted to lie on opposite sides of a rail. These runners are provided near their rear ends with a rail-lifting member, and they extend forwardly from that member a sufficient distance to overlie the pavement adjacent the rail at the point where initial lifting of the rail occurs. The forward ends of the runners are held down against the surface of the pavement, as by the weight of the tractor which pulls them. The rail-lifting member rides beneath a lifted portion of the rail when the device is pulled forwardly by the tractor and lifts the rail ahead of such member. At the same time, forward portions of the runners hold the adjacent pavement in place, so that only narrow strips of pavement along each side of the rail are disturbed.

For initially raising the end of a rail into position over the rail-lifting member, any suitable means may be used, but in the preferred form of my invention I associate with the runners a truck-crane, carried by the truck or other tractor used to pull the runners. The free end of the boom of such crane is supported from the run-

ners, and the hoist of the crane may then be used in co-operation with the runner structure in the rail lifting operation. Thus, it may be used for initially lifting the end of a rail into position to be engaged by the rail-engaging member on the runners, and for certain other operations. In addition, the truck crane may be used to lift the runners off the ground so that they may be transported.

The accompanying drawing shows a preferred form of machine embodying my invention. In such drawing, Fig. 1 is a side elevation of the machine, with parts broken away to expose the rail to full view; Fig. 2 is a plan of the machine shown in Fig. 1, but with the crane and portions of the tractor omitted; Fig. 3 shows the lifting sheave of the crane in association with a pair of rail-lifting tongs; and Fig. 4 is an end elevation of the device of Fig. 1, with parts broken away to show certain details of construction.

The machine is shown in place on a pavement 10. Beneath this pavement 10 are ties 11 to which the rail 12 is held by spikes 13 and from which it is being removed. The two runners 14 rest on the pavement on opposite sides of the rail 12, and they are spaced from the rail a sufficient distance to clear the flanges of the rail. They are desirably spaced more than just sufficient to clear the rail, and this spacing depends upon the type of pavement, since some pavement will inevitably be torn up in pulling the rail out of its embedded position in the pavement, and the amount will depend on the type of pavement. Where the pavement adjacent the rail is of brick, I desirably space the runners so that they clear two bricks on each side of the rail if those bricks are laid parallel with the rail, or one brick on each side of the rail if those bricks are laid perpendicular to the rail. With asphalt pavement which extends up to the rail this spacing can be somewhat less, for asphalt pavement is usually easier to break. With concrete pavement which extends up to the rail, it sometimes is desirable to first break, as with air hammers, a strip of pavement along each side of the rail. In that case, the runners are spaced so that they rest on unbroken pavement.

The runners 14 are held in spaced relationship by means of cross members 15 located near the front ends of the runners. Near their rear ends, the runners are arranged to support a rail-lifting member. This may be a shoe or slide adapted to have a lifted portion of a rail slide over it. It may also be a shaft, which may carry a roller. As shown, the runners are provided

with bearings for the reception of a shaft 16 which carries a roller 17, disposed on that shaft between the runners. Desirably, there is more than one set of bearings for the shaft 16, at different distances from the lower surface of the runners 14. A convenient arrangement is shown, in which a lower set of bearings are holes or upwardly open notches 18 cut in the runners near their rear ends. An upper set of bearings 19, also open at the top, are fixed on and above the runners, ahead of the lower set of bearings. This possibility of adjustment is desirable, for while the roller is best positioned at as low a point as possible, it must be high enough to clear the debris resulting from the rail-pulling operation, and the amount of such debris and the size of pieces in such debris depends upon the type of pavement involved.

The runners 14 must be heavy and stiff. They are desirably of iron, and may be either built up or of some standard shape. I consider especially suitable beams formed of a pair of channels fastened back to back, and have used beams built up of four Z bars fastened to a plate, to form a beam twelve inches in vertical thickness. Of the standard shapes, I consider an H beam especially suitable, for it combines strength and rigidity with flange walls which will lie flat on the pavement, and will give a good bearing surface. Such H beam runners also provide inwardly open channel passages lengthwise of the runners, through which debris from the rail lifting operation may pass out to the rear. The forward ends of the runners 14 desirably have their lower corners cut away, and the lower flanges curved upwardly so that the runners will ride over any slight obstruction.

The runner structure is pulled by a tractor, and for this purpose I provide near the front of the runners a heavy cross member such as a bar 20 by which the runner structure may be secured to a tractor. The tractor used may be of any convenient type, either of the track-type or of the wheel-type. The tractor is desirably fairly heavy, and may be weighted if necessary; for the forward ends of the runners extend beneath the tractor so that the weight of the tractor will serve to hold those runners down.

I have used a heavy truck to pull the runners, and show in the drawing a portion of a tractor of this sort. The truck is positioned with its rear axle 21 over the forward ends of the runners, and the runners are secured thereto by means of cables 22 extending around the bar 20 and around the axle 21. Desirably, there is some clearance between the axle and the runners, for this insures good traction but still limits upward movement of the forward ends of the runners.

While the structure heretofore described is sufficient for most operations involved in rail removal, the preferred form of my device embodies certain other structures.

In such preferred embodiment of my invention, the tractor carries a crane. The boom 30 of the crane extends rearwardly over the runners 14 and its free end is secured to the upper ends of uprights 31 supported on the rear ends of the runners 14 and fastened thereto, desirably by a connection which is not rigid. As shown, the runners carry angles 25 fastened as by rivets to the runners and lying within the channel of the uprights 31. A bolt 26 passing through a hole in the web of each channel-shaped upright 31 and through a vertically elongated hole in the upright leg of the associated angle 25 fastens the

upright to the runner. The elongation of the hole in the angle permits the upright some freedom of pivotal movement, so that no forward pull on the runners is transmitted through the boom.

The boom 30 is arranged to be lifted by the boom line 32 so that the runners and parts carried by them can be lifted bodily when it is desired to transport them from place to place. To assist in this lifting of the runners off the ground, some means is desirably provided near the front end of the runners for lifting those front ends. Such means is desirably also useful to hold the runners rearwardly with respect to the truck when, as occasionally happens, it is necessary to move the runners backward. This means may be a releasable connection between the runners and a point on the boom near its pivot point 33, but more conveniently, I provide a winch 34 either as part of the crane or (as shown) on the rear end of the truck frame. This winch 34 may be either hand operated by a handle 36 or may be power-operated. It conveniently has two cables the ends of which are provided with hooks adapted to be received in eyes 35 mounted on the runners 14.

The hoist of the crane has its sheaves 37 and 38 positioned close to, and desirably between, the uprights 31. The movable sheave 38 supports a lifting hook 39 which is adapted to receive a pair of rail-lifting tongs 40. The hoist sheaves 37 and 38 have associated with them a hoist cable 41 which extends to a power-operated drum carried by the truck.

In using my device, the runners are positioned on opposite sides of the rail which is to be removed, and spaced apart a distance suitable to the pavement in which the rail is embedded. The rear ends of the runners are positioned adjacent an end of the rail to be removed, or if no free end is available, then the rail is cut. With the roller 17 and its shaft 16 removed the rail-lifting tongs 40 are brought into engagement with the rail near a free or cut end, and the tongs are then lifted by means of the crane hoist. When the rail has been lifted a sufficient distance to permit it, the roller 17 and shaft 16 are replaced, and the rail is then lowered and permitted to rest on the roller 17. The lifting tongs 40 are then removed. The tractor is then operated to pull the runners forwardly. As they move forwardly the roller 17 rolls beneath the lifted portion of the rail 12 and lifts the rail ahead of the roller. The runners 14 extend far enough forward in engagement with the pavement alongside the rail so that they overlie the pavement at the point where initial rail-lifting occurs. They are held down by the rail reaction and by the weight of the tractor, and they hold the pavement in place alongside the rail while the rail is being lifted out of such pavement. Narrow strips of pavement immediately adjacent the rail are torn out during this operation, and the spikes which hold the rail on the ties are pulled out of such ties. These spikes, and the debris from the broken strips of pavement, pass out between the runners 14 and beneath the roller 17 and are left largely piled in place in the narrow break in the pavement.

In some track, rail sections are fastened together with fish plates which extend below the base flanges of the rail, or the rail has fastened to it other devices which extend below those base flanges. Such devices, under operating conditions, will not readily pass over the roller or other rail-lifting member. When that is the case, the

hoist will co-operate in the lifting operation. The tongs may be brought into engagement with the rail adjacent such devices as they approach the roller. The rail may then be lifted by the hoist the small extra amount necessary to permit the rail lifting member to pass under the downwardly extending portion of the device. The tractor may then continue its forward pull, and as soon as the obstructing device lies above the roller, the hoist and tongs may be released. In actual operation, this retards progress but very little. Usually, it is not even necessary to stop forward movement to permit removal of the tongs, for they may usually be removed simply by operation of the crane hoist alone.

In addition, the rails of a track are usually interconnected at some points by spacing bars. I have found that in many cases these will break, but usually it is desirable to cut them, either when they are encountered in the rail lifting operation, or by locating them and cutting them ahead of the rail lifting operation. A single cut is all that is necessary, for even if it be close to one rail, the rest of the bar will pull out with the opposite rail.

I have found that with my device it is possible to remove rails substantially continuously at the rate of from two to four miles an hour, and to travel for blocks at a time without any stop. On some occasions, however, especially with very old rail, the rail will break, either at a joint or elsewhere. In that case, the device is moved forward so that it clears the broken-off rail and the rail-lifting tongs 40 and the hoist hook 39 are again used to lift the end of the still-embedded portion of the rail. This operation, however, is relatively simple, and even though it must be repeated several times in a block, rail removal with my device is much more rapid than with any other arrangement of which I am aware.

In addition to the rapidity with which my device operates, however, it has the further advantage that only a small portion of the pavement is disturbed. This small portion can be readily repaired and the street can be continued in use without complete re-paving, and even without paving of the whole area between the rails. Moreover, because of the rapidity with which my device operates, and because of the fact that it disturbs a minimum portion of the pavement, it is necessary in most cases to take the street out of service for only short periods of time. Indeed, in some cases portions of the street have continued in use, save for the immediate block in which my device has been operating. In addition, where the device is operated only during the day time, the runners can readily be picked up and transported by the tractor away from even that one block, so that the side lanes of the street can be used during the night.

I claim as my invention:

1. A device for lifting rails embedded in a pavement, comprising a pair of runners adapted to rest on, and to be moved along the pavement on opposite sides of a rail to be lifted, a rail supporting member on said runners and adapted to move beneath and lift the rail as the runners are moved, said runners extending forwardly of said member to overlie the pavement at the point of initial movement of the rail, and means restraining upward movement of said runners at said point, to limit the amount of pavement disturbed by the movement of the rail out of said pavement.

2. A device for lifting rails embedded in a pave-

ment, comprising a pair of runners adapted to rest on, and to be moved along the pavement on opposite sides of a rail to be lifted, a rail supporting member on said runners and adapted to move beneath and lift the rail as the runners are moved, said member being spaced above the pavement-engaging surface of said runners sufficiently to clear debris created by the rail-lifting, said runners extending forwardly of said member to overlie the pavement at the point of initial movement of the rail, and means restraining upward movement of said runners at said point, to limit the amount of pavement disturbed by the movement of the rail out of said pavement.

15 3. A device for lifting rails embedded in a pavement, comprising a pair of runners adapted to rest on, and to be moved along the pavement on opposite sides of a rail to be lifted, a rail supporting member on said runners and adapted to move beneath and lift the rail as the runners are moved, said runners extending forwardly of said member to overlie the pavement at the point of initial movement of the rail, and a tractor for pulling said runners and acting on the forward ends of said runners to restrain with its weight upward movement thereof.

20 4. A device for lifting rails embedded in a pavement, comprising a pair of runners adapted to rest on, and to be moved along the pavement on opposite sides of a rail to be lifted, a rail supporting member on said runners and adapted to move beneath and lift the rail as the runners are moved, said member being spaced above the pavement-engaging surface of said runners sufficiently to clear debris created by the rail-lifting, said runners extending forwardly of said member to overlie the pavement at the point of initial movement of the rail, and a tractor for pulling said runners and acting on the forward ends of said runners to restrain with its weight upward movement thereof.

25 5. A device for lifting rails in a continuous operation, comprising a pair of runners adapted to lie on opposite sides of a rail over the ties to which said rail is secured, a rail-engaging member on said runners and adapted to be advanced beneath a lifted portion of the rail to lift the rail ahead of said member, said runners extending forwardly of said member to the point of initial movement of the rail, means for restraining the forward ends of said runners against upward movement, to hold in place said ties and the material in which they are laid.

30 6. A device for lifting rails in a continuous operation, comprising a pair of runners adapted to lie on opposite sides of a rail over the ties to which said rail is secured, a rail-engaging member on said runners and adapted to be advanced beneath a lifted portion of the rail to lift the rail ahead of said member, said runners extending forwardly of said member to the point of initial movement of the rail, and a tractor for pulling said runners and acting on the forward ends of said runners to restrain with its weight upward movement thereof.

35 7. A device for lifting a rail embedded in a pavement, comprising a movable rail-support spaced upwardly from the pavement and adapted by forward movement beneath a lifted portion of the rail to lift the rail ahead of said support, means overlying the pavement on opposite sides of the rail over the portion where initial movement occurs to hold said pavement against being disturbed by said lifting, said hold-down means being restrained against upward movement by the

resistance of the rail to lifting, and a tractor to pull said rail-support and acting on said hold-down means to restrain with its weight upward movement thereof.

8. A device for lifting a rail embedded in a pavement, comprising a movable rail-support spaced upwardly from the pavement and adapted by forward movement beneath a lifted portion of the rail to lift the rail ahead of said support, means overlying the pavement on opposite sides of the rail over the portion where initial movement occurs to hold said pavement against being disturbed by said lifting, and a tractor to pull said rail-support and acting on said hold-down means to restrain with its weight upward movement thereof. 5

9. A device for lifting rails as defined in claim 3 in combination with means carried by said tractor for lifting said runners off the pavement for transport.

10. A device for lifting rails as defined in claim 6 in combination with means carried by said tractor for lifting said runners off the pavement for transport.

11. A device for lifting rails as defined in claim 3, in combination with hoist mechanism supported by said runners above said rail-supporting member, and power operating mechanism for said hoist carried by said tractor, said hoist being adapted to lift a rail to position for engagement on said rail-supporting member. 25

12. A device for lifting rails as defined in claim 3, in combination with hoist mechanism supported by said runners above said rail-supporting member, said hoist being adapted to lift a rail to position for engagement on said rail-supporting member. 30

13. A device for lifting rails as defined in claim 3, in combination with a hoist boom on said tractor, means on said runners for supporting the free end of said boom and connecting said boom to said runners, lift means on said boom in posi- 40

tion to lift a rail to position for engagement on said rail-supporting member, and operating mechanism on said tractor for said lift means and for lifting said boom to lift said runners for transport, said operating mechanism being positioned to aid with its weight in restraining upward movement of the forward ends of said runners.

14. A device for lifting rails, comprising a pair of runners adapted to lie on opposite sides of a rail to be lifted and to overlie the rail bed at a point of initial movement of the rail as it is pulled to limit disturbance of said rail bed during the rail-lifting operation, a hoist adapted to lift a rail between said runners and to react against said runners, a tractor for moving said runners, and hoist-operating mechanism supported on said tractor.

15. A device for lifting rails, comprising a pair of runners adapted to lie on opposite sides of a rail to be lifted and to overlie the rail bed at a point of initial movement of the rail as it is pulled to limit disturbance of said rail bed during the rail-lifting operation, a mobile crane associated with said runners and positioned to aid with its weight to restrain upward movement of said runners, the hoist mechanism of said crane being connected with said runners to exert hoist-reaction downwardly against said runners. 20

16. A device for lifting rails, comprising hold-down runners adapted to overlie a rail-bed over areas adjacent to the sides of a rail to be lifted and adapted to be moved along the rail-bed, said runners extending forwardly to the point of initial movement of the rail to limit disturbance of said rail-bed as said rail is lifted therefrom, and hoist-mechanism associated with said hold-down means to restrain with its weight upward movement of the forward ends of said runners and arranged to exert hoist reaction downwardly against said runners at a rearward point thereon. 35
